Primary Examiner—Melvin B. Feifer*Assistant Examiner*—Philip Hyder*Attorney, Agent, or Firm*—Melvin I. Stoltz**[57] CLAIM**

The ornamental design for a spike removing tool, as shown and described.

DESCRIPTION

FIG. 1 is a perspective view of the spike removing tool showing my new design;

FIG. 2 is a top plan view thereof;

FIG. 3 is a front elevational view thereof;

FIG. 4 is a side elevational view thereof looking from the right side of FIG. 2, the opposite side being identical in appearance; and,

FIG. 5 is a bottom plan view thereof.

FIG. 1

FIG. 2

FIG. 5

FIG. 3

FIG. 4
